(57) **CLAIM**

The ornamental design for an apportion cap, as shown and described.

DESCRIPTION

FIG. 1 is a top front left side perspective view of an apportion cap showing the claimed design;

FIG. 2 is right side view of that seen in FIG. 1;

FIG. 3 is a left side view of that seen in FIG. 1;

FIG. 4 is a front side view of that seen in FIG. 1;

FIG. 5 is a back side view of that seen in FIG. 1;

FIG. 6 is a top side view of that seen in FIG. 1;

FIG. 7 is a bottom side view of that seen in FIG. 1;

FIG. 8 is bottom right side perspective view of that seen in FIG. 1; and,

FIG. 9 is bottom left side perspective view of that seen in FIG. 1.

The dash, space, dash type broken lines are included for illustrating portions of the apportion cap that form no part of the claimed design.

1 Claim, 5 Drawing Sheets
